(57) **CLAIM**

The ornamental design for a microphone cartridge, as shown and described.

DESCRIPTION

FIG. 1 is a first top perspective view of the microphone cartridge of in accordance with a first embodiment;
FIG. 2 is a second top perspective view thereof;
FIG. 3 is a first bottom perspective view thereof;
FIG. 4 is a second bottom perspective view thereof;
FIG. 5 is a first side elevational view thereof, the opposing side being a mirror image of FIG. 5;
FIG. 6 is a second side elevational view thereof, the opposing side being a mirror image of FIG. 6;
FIG. 7 is a top plan view thereof;
FIG. 8 is a first top perspective view of the microphone cartridge of in accordance with a second embodiment;
FIG. 9 is a second top perspective view thereof;
FIG. 10 is a first bottom perspective view thereof;
FIG. 11 is a second bottom perspective view thereof;
FIG. 12 is a first side elevational view thereof, the opposing side being a mirror image of FIG. 12;
FIG. 13 is a second side elevational view thereof, the opposing side being a mirror image of FIG. 13; and,
FIG. 14 is a top plan view thereof.
The broken lines in the drawings illustrate the portions of the design that form no part of the claim.
